[57] CLAIM

The ornamental design for a cutoff insert, as shown and described.

DESCRIPTION

FIG. 1 is a top, front and right side perspective view of a cutoff insert showing our new design;
FIG. 2 is a top, rear and right side perspective view;
FIG. 3 is a front elevational view;
FIG. 4 is a bottom plan view;
FIG. 5 is a right side elevational view;
FIG. 6 is a top plan view;
FIG. 7 is a rear elevational view; and,
FIG. 8 is a left side elevational view thereof.
FIGS. 1 and 2 have been drawn on an enlarged scale with respect to FIGS. 3-8.

FIG. 1

FIG. 2

FIG. 3

FIG. 4

FIG. 5

FIG. 7

FIG. 6

FIG. 8
